UNITED STATES PATENT OFFICE

133,004

DESIGN FOR A DOOR FASTENER

Paul W. Wortman, Los Angeles, Calif.

Application November 6, 1941, Serial No. 104,054

Term of patent 7 years

To all whom it may concern:

Be it known that I, Paul W. Wortman, a citizen of the United States, residing in Los Angeles, in the county of Los Angeles and State of California, have invented a new, original, and ornamental Design for a Door Fastener, of which the following is a specification, reference being had to the accompanying drawing, forming part thereof.

Fig. 1 is a perspective view of a door fastener, showing my new design.

Fig. 2 is a side elevational view of said device.

Fig. 3 is an end elevational view of said device.

Fig. 4 is a plan view of the device.

I claim:

The ornamental design for a door fastener, substantially as shown.

PAUL W. WORTMAN.
